(57) **CLAIM**

The ornamental design for a pitch tool wrench, as shown and described.

DESCRIPTION

FIG. 1 is a top perspective view of a pitch tool wrench as claimed herein, with the wrench portion in a closed position; FIG. 2 is a top perspective view thereof, with the wrench portion in an open position;

FIG. 3 is a back side view of the pitch tool wrench with the wrench portion in a closed position;

FIG. 4 is a front side view thereof;

FIG. 5 is a right side view thereof;

FIG. 6 is a left side view thereof;

FIG. 7 is a top plan view thereof; and,

FIG. 8 is a back plan view thereof.

The broken line showing is included for the purpose of illustrating and forms no part of the claimed design.
